UNITED STATES PATENT OFFICE.

GEORGE BREED, OF PHILADELPHIA, PENNSYLVANIA, ASSIGNOR TO THE LYRACHORD COMPANY, A CORPORATION OF NEW YORK.

ELECTROMAGNETIC MUSICAL INSTRUMENT.

1,174,813.

Specification of Letters Patent.

Patented Mar. 7, 1916.

Application filed March 29, 1912. Serial No. 687,010.

To all whom it may concern:

Be it known that I, GEORGE BREED, a citizen of the United States, residing at Philadelphia, in the county of Philadelphia and 5 State of Pennsylvania, have invented a new and useful Electromagnetic Musical Instrument, of which the following is a specification.

My invention relates to musical instruments wherein sonorous members are caused to vibrate by electro-magnets excited by pulsating currents and its primary object is to enable the performer to increase the volume of any note desired with resulting solo effect, 15 particularly in playing an automatic piano.

In its preferred form, my improved mechanism comprises the combination with the strings, of an automatic piano adapted for using perforated sheet music and electro- 20 magnetic means adapted for vibrating such strings, of means adapted to be operated in accordance with a record on said sheet for increasing the current exciting particular electro-magnets and thereby increasing the 25 force acting upon the corresponding strings with resulting increased volume of tone.

The characteristic features of my improvements are fully disclosed in the following description and the accompanying drawings in illustration thereof.

Referring to the drawing forming part of this application, the figure is a diagrammatic representation of mechanism embodying my invention.

In the drawing, 1, 1^a, 1^b, and 1^c represent in diagram a number of the piano strings combined with which are the respective electro-magnets 2, 2^a, 2^b and 2^c, which are connected by the conductors 3, 3^a, 3^b, and 3^c with 35 the main conductor 4 and by the conductors 5, 5^a, 5^b and 5^c with the respective resilient contacts 6, 6^a, 6^b and 6^c, the conductor 4 being connected at one end with a battery 7, or other source of electrical energy, and at the 40 other end having an extension 4^a which is connected with the contact 8, 8^a and 8^b, and through the resistance coils 9 and 9^a with the contacts.

A conductor 10, connected to the battery 45 through the switch 10^a, is connected with a conductor 11 terminating in a resilient contact 12 and containing a pulsator 13; with a conductor 11^a terminating in a resilient contact 12^a and containing a pulsator 13^a; with 50 a conductor 11^b terminating in a resilient

contact 12^b and containing a pulsator 13^b; and with a conductor 11^c terminating in a resilient contact 12^c and containing a pulsator 13^c.

Resilient contacts 14, 14^a, 14^b, and 14^c are 60 connected with respective conductors 15, 15^a, 15^b and 15^c containing the respective resistances 16, 16^a, 16^b and 16^c and terminate in the resilient contacts 17, 17^a, 17^b and 17^c, the latter contacts being fixed on a rail 18 of insulating material and being electrically separated. Contacts 19, 19^a, 19^b and 19^c, fixed to the rail and electrically separated, are normally engaged by the respective contacts 17, 17^a, 17^b and 17^c and normally engage a 70 conducting bridge 20 fixed on a revoluble cylinder 21. With this bridge the contacts 8, 8^a, and 8^b are adapted to engage simultaneously so as to cut out the resistances 9 and 9^a; or, by turning the cylinder in the direction of the arrow thereon, the contacts 8 and 8^a are successively disengaged from the bridge and the resistances 9 and 9^a cut in successively.

The cylinder 21 is turned by an eccentric 80 pin 22 which is connected with a push rod 23 having thereon a button 24 acting against a spring 25, whereby the bridge is held normally in engagement with all the contacts 8, 8^a and 8^b.

The circuits containing the respective contacts 17, 17^a, 17^b and 17^c are broken by lifting such contacts from engagement with the corresponding contacts 19, 19^a, 19^b and 19^c, which is effected by a traveler 26 adapted to 90 slide on a rail 27 and which traveler has a non-conducting crown or curved top 26^a. A rod 28 connects the traveler 26 with an arm 29 on a shaft 30 adapted to turn in bearings 31 and having the arm 32 thereon. A rod 33 connects the arm 29 with an arm 34 on a shaft 35 which is turned in the bearings 36 by a handle 37. A rod 38 connects the arm 32 with a bar 39 which is movable longitudinally through the bearing 40 and has the pointer 41 thereon which is movable parallel to the tracker bar 42. The traveling perforated sheet 43 is provided with a record, as the line 44, with which the pointer 41 can be 100 kept in registration by manipulating the handle 37. During this operation, the traveler 26 is correspondingly moved to elevate the desired contacts 17, 17^a, 17^b or 17^c, corresponding to the particular electro-magnet 105 which it is desired to energize so as to 110

accentuate its action and increase the amplitude of vibration of the corresponding string.

In the operation of the instrument, the vertically movable abstracts 45, 45^a, 45^b and 45^c of the piano actions act through their respective lugs 46, 46^a, 46^b and 46^c, on the corresponding contacts 12, 12^a, 12^b and 12^c, which, upon a limited upward movement of the abstracts, engage the respective contacts 6, 6^a, 6^b and 6^c, and upon a further upward movement the contacts 6, 6^a, 6^b and 6^c engage the respective contacts 14, 14^a, 14^b and 14^c.

The switch 10^a being closed and the abstract 45 elevated to effect the engagement of the contact 12 with the contacts 6 without engaging the latter with the contact 14, current passes from the battery 7, through the electro-magnet 2, by way of the parts 3, 5, 6, 12, 11, 13, 10, and 10^a, whereby the string 1 is sounded. Upon further elevating the abstract 45 to effect the engagement of the contact 6 with the contact 14, a desired proportion of the current (determined by the resistance 16) is shunted around the electro-magnet 2, passing through the parts 4^a, 8, 20, 19, 17, 15, 16, 14, 6, 12, 11, 13, 10 and 10^a. If the lever 37 be operated (in correspondence with the record on the sheet 43) to move the traveler 26 under the contact 17 and disengage it from the contact 19, the shunt circuit around the electro-magnet 2 will be broken, the larger amount of current will flow through this electro-magnet 35 and the resulting greater electro-magnetic force exerted thereby upon the string 1 will result in the production of a louder note. With the contact 17 in the elevated position and the instrument operated so that the several abstracts effect the engagement of the respective contacts 6, 6^a, 6^b and 6^c with the corresponding contacts 14, 14^a, 14^b and 14^c, full current will pass through the electro-magnet 2, while reduced current will pass through the remaining electro-magnets 2^a, 2^b and 2^c, because, with respect to the electro-magnet 2^a, current, which would otherwise pass therethrough, is shunted by way of the parts 4^a, 8, 20, 19^a, 17^a, 15^a, 14^a, 6^a, 12^a, 11^a, 13^a, 10 and 10^a; with respect to the electro-magnet 2^b, current which would otherwise pass therethrough is shunted by way of the parts 4^b, 8, 20, 19^b, 17^b, 15^b, 14^b, 6^b, 12^b, 11^b, 13^b, 10 and 10^b; and with respect to the electro-magnet 2^c, current, which would otherwise pass therethrough, is shunted by way of the parts 4^c, 8, 20, 19^c, 17^c, 15^c, 16^c, 14^c, 6^c, 12^c, 11^c, 13^c, 10 and 10^c. In a similar manner, solo notes are produced by the respective strings 1^a, 1^b, and 1^c, by shifting the traveler 26 and elevating the corresponding contacts 17^a, 17^b and 17^c. It will be understood that by pushing in the button 24 and turning the cylinder 21 until the bridge is withdrawn from the con-

tact 8, the resistance 9 is cut into the shunt circuits, the current is divided so that a smaller amount thereof flows through such circuits, and a larger amount through the complementary circuits containing the respective electro-magnets, with the production of louder notes by the corresponding strings. When the button is pushed in farther, so that the bridge 20 is withdrawn from the contact 8^a, resistances 9 and 9^a are cut into the shunt circuits with corresponding reduction of the current flowing therethrough and increased current in the complementary circuits containing the electro-magnets, with production of louder tones by 8c the corresponding strings. Hence the relation of the accompaniment to the solo notes may be varied. By turning the bridge 20 so as to withdraw it from the contacts 8, 8^a and 8^b, the shunt circuits are broken and the 85 solo action eliminated.

While the drawing is diagrammatic, it is understood of course, that the invention is especially adapted to be applied to a piano in which the strings and actions are arranged in the ordinary way, and which piano can be played automatically from a perforated note-sheet running over a tracker and that the button and lever are arranged in a convenient position thereon for manual 95 manipulation.

The details of such an instrument are shown more fully in a previous application for patent filed by me March 20, 1912, Serial No. 684,922.

The details and arrangements herein shown and described may be greatly varied by a skilled mechanic without departing from the scope of my invention as expressed in the claims.

Having thus fully described my invention, what I claim and desire to secure by Letters-Patent is:

1. In a musical instrument, the combination of the strings, a set of electromagnets, and corresponding pulsators for vibrating the strings, and a single device effective to vary the current flowing through any selected magnet in said set at the will of the performer, whereby a solo effect may be attained.

2. In a musical instrument, the combination of the strings, a set of electromagnets and corresponding pulsators for vibrating the strings, a main circuit including a source of electricity, a branch circuit for each electromagnet and associated pulsator, a shunt circuit for each branch circuit connected in parallel with said magnet and effective when closed to reduce the current flowing through said magnet, and a single means effective to decrease the current flowing in any selected shunt circuit at the will of the performer, thereby increasing the current passing through the corresponding magnet and in-

creasing its effect upon the corresponding string, whereby a solo effect may be attained.

3. In an automatic piano, the combination of a perforated note sheet, a set of strings, a set of electromagnets and pulsators for vibrating said strings, and a single means adapted to be manually operated in accordance with indications on the note sheet and effective to increase the current flowing in any selected electro-magnet at the will of the performer thereby increasing the force acting upon the corresponding string to produce a solo effect.

4. In a musical instrument, the combination of the strings, a set of electromagnets and corresponding pulsators for vibrating the strings, a main circuit including a source of electricity, a branch circuit for each electromagnet and associated pulsator, a shunt circuit for each branch circuit connected in parallel with said magnet and effective when closed to reduce the current flowing through said magnet, said separate shunt circuits having one portion in common, and means to vary the resistance of said common portion.

5. In a musical instrument, the combination of the strings, a set of electro-magnets and corresponding pulsators for vibrating the strings, a main circuit including a source of electricity, a branch circuit for each electromagnet and associated pulsator, a shunt circuit for each branch circuit connected in parallel with said magnet and effective when closed to reduce the current flowing through said magnet, said separate shunt circuits having one portion in common, and means to vary the resistance of said common portion or to open the circuit there-

40 through.

6. In a musical instrument, the combination of the strings, a set of electromagnets and corresponding pulsators for vibrating the strings, a main circuit including a source of electricity, a branch circuit for each electromagnet and associated pulsator, a shunt circuit for each branch circuit connected in parallel with said magnet and effective when closed to reduce the current flowing through said magnet, said separate shunt circuits having one portion in common, means to vary the resistance of said common portion, and a single device effective to open any selected shunt circuit at the will of the performer without disturbing the remaining shunt circuits.

7. In a musical instrument, the combination of the strings, a set of electromagnets and corresponding pulsators for vibrating the strings, a main circuit including a source of electricity, a branch circuit for each electromagnet and associated pulsator, a shunt circuit for each branch circuit connected in parallel with said magnet and effective when closed to reduce the current flowing through

said magnet, said separate shunt circuits having one portion in common, means to open said common portion or to vary the resistance thereof, and additional means effective to open any selected shunt circuit at 70 the will of the performer thereby increasing the flow of current through the associated electromagnet and producing a solo effect.

8. In a piano, the combination of the strings, a set of electromagnets and pulsators for vibrating the strings, a branch circuit for each of said electromagnets, a corresponding shunt circuit for diminishing the current passing through said magnet, circuit closing devices for each branch circuit, and means whereby the shunt circuit associated with any selected magnet may be disconnected to increase the flow of current through said magnet without disturbing the remaining shunt circuits.

9. In a piano, the combination of the strings, a set of electromagnets and pulsators for vibrating the strings, a branch circuit for each of said electromagnets, a corresponding shunt circuit for diminishing the current passing through said magnet, circuit closing devices, manually operated means effective to open the shunt circuit associated with a selected electromagnet, a perforated note sheet, and an indicating device adapted to coöperate with a record on said note sheet and connected to said manually-operated circuit-opening means.

10. In a piano adapted to be operated from a perforated note sheet, the combination of the perforated note sheet, the strings, a set of electromagnets and pulsators for vibrating the strings, a main circuit including a source of electricity, a branch circuit for each electromagnet and associated pulsator, a shunt circuit for each branch circuit connected in parallel with said magnet and effective when closed to reduce the current flowing through said magnet, circuit closing devices for each branch circuit, a contact in each shunt circuit, and manually operated means whereby any particular contact can be disengaged and the current exciting the corresponding electromagnet can be thereby increased in force without disturbing the connections for the remaining magnets.

11. In a piano adapted to be operated from a perforated note sheet, the combination of the perforated note sheet, the strings, a set of electromagnets and pulsators for vibrating the strings, a main circuit including a source of electricity, a branch circuit for each electromagnet and associated pulsator, a shunt circuit for each branch circuit connected in parallel with said magnet and effective when closed to reduce the current flowing through said magnet, circuit closing devices for each branch circuit, a contact in each shunt circuit, a traveler for disengag-

ing any selected contact, and manually operated means for moving said traveler.

12. In a piano adapted to be operated from a perforated note sheet, the combination of

- 5 the perforated note sheet, the strings, a set of electromagnets and pulsators for vibrating the strings, a main circuit including a source of electricity, a branch circuit for each electromagnet and associated pulsator,
- 10 a shunt circuit for each branch circuit connected in parallel with said magnet and effective when closed to reduce the current flowing through said magnet, circuit closing devices for each branch circuit, a contact in
- 15 each shunt circuit, a traveler for disengaging any selected contact, manually operated means for actuating said traveler, and an indicator connected to said means and adapted to coöperate with the markings on the
- 20 perforated note sheet.

- 13. In a piano adapted to be operated from a perforated note sheet, the combination of the perforated note sheet, the strings, a set of electromagnets and pulsators for vibrating the strings, a main circuit including a source of electricity, a branch circuit for each electromagnet and associated pulsator, a shunt circuit for each branch circuit connected in parallel with said magnet and effective when
- 25 closed to reduce the current flowing through said magnet, circuit closing devices for each branch circuit, a contact in each shunt circuit, a traveler for disengaging any one of said contacts, manually operated means for actuating said traveler, an indicator connected to said means and adapted to co-
- 30
- 35

operate with the markings on the note sheet, and means for varying the resistance of all of said shunt circuits simultaneously.

14. In a musical instrument, the combination of the strings, a set of electromagnets and pulsators for vibrating the strings, current supplying means, and a single means effective to vary the current supply to a selected magnet without changing the current supply to the remaining magnets.

15. In a musical instrument, the combination of the strings, a set of electro-magnets and pulsators for vibrating said strings, means for supplying a substantially equal amount of current to the respective electro-magnets, automatic mechanism for controlling the current supplying means, and manually operated means for causing an increased amount of current to be supplied to any desired electro-magnet with the production of a solo effect.

16. In a musical instrument, the combination of the strings, a set of electro-magnets and pulsators for vibrating said strings, means comprising a perforated sheet for effecting the desired action of said electro-magnets, and manually operated mechanism whereby the action of any desired electro-magnet can be varied.

In testimony whereof I have hereunto set my hand, in the presence of two subscribing witnesses.

GEORGE BREED.
